ATTORNEY.

UNITED STATES PATENT OFFICE

116,162

DESIGN FOR A MASSAGE BRUSH

Robert W. Hall, Los Angeles, Calif.

Application March 11, 1939, Serial No. 83,511

Term of patent 14 years

To all whom it may concern:

Be it known that I, Robert W. Hall, a citizen of the United States, residing at Los Angeles, county of Los Angeles, in the State of California, have invented a new, original, and ornamental Design for Massage Brush, of which the following is a specification, reference being had to the accompanying drawing, forming part thereof.

Fig. 1 is a top plan view of the massage brush showing my new design; and

Fig. 2 is a side elevational view thereof.

I claim:

The ornamental design for a massage brush, substantially as shown.

ROBERT W. HALL.
